UNITED STATES PATENT OFFICE.

LYCURGUS D. FORBES, OF STRANGER, TEXAS.

GOVERNOR FOR COTTON-GINS AND COTTON-GIN FEEDERS.

SPECIFICATION forming part of Letters Patent No. 241,470, dated May 10, 1881.

Application filed April 14, 1881. (Model.)

To all whom it may concern:

Be it known that I, LYCURGUS D. FORBES, of Stranger, in the county of Falls and State of Texas, have invented certain new and useful Improvements in Governors for Cotton-Gins and Cotton-Gin Feeders; and I do hereby declare the following to be a full, clear, and exact description of the invention, such as will enable others skilled in the art to which it pertains to make and use it, reference being had to the accompanying drawings, which form part of this specification.

My invention relates to an improvement in governors for cotton-gins and cotton-gin feeders; and it consists, first, in the combination of an oscillating or movable roll-breast with a regulating attachment, whereby the size of the roll or the pressure of the cotton in the roll-box is made to regulate the feed to the gin to any desired degree; second, in forming a series of slots through the outer side of the roll-breast, so that the cotton-seed may be discharged through the outer side of the breast, as well as in addition to the usual slot which is made through the bottom of the roll-box; third, the combination of an oscillating or a yielding roll-breast, a series of connecting-levers, a scale to indicate the pressure, and a mechanism for throwing the feeder out of gear whenever the pressure in the roll-box exceeds a given amount, all of which will be more fully described hereinafter.

The object of my invention is to produce a governor for cotton-gins and cotton-gin feeders, so that there will always be a certain-sized roll or pressure of cotton in the roll-box, which is about the full capacity of the machine to gin, and which governor will throw the feeder out of gear should the cotton be fed into the roll-box so that the pressure of the cotton exceeds the given amount, whereby the gin is kept working at its full capacity all the time without the slightest danger of its choking or being injured.

Figure 1 is an end view of a machine embodying my invention. Fig. 2 is a plan view of the same. Fig. 3 is a side elevation taken through the outer side of the roll-box. Figs. 4, 5, and 6 are detail views of the same.

My invention is placed upon the top of the cotton-gin, which has been prepared for it. Should it be desired to apply the machine to a gin which has not been built especially for use in connection with my invention, it is only necessary to remove the roll-breast and then apply my invention upon the top of the gin, so that the roll-breast A will take the place of the roll-breast which is removed. The breast A, instead of being made a rigid part of the machine, is here placed lightly upon the machine, so that it can be turned back out of the way, or will have a back-and-forth or oscillating motion, so as to contract or enlarge the size of the roll-box, according to the pressure of the cotton. This roll-box A has secured to each of its ends an iron casting, B, which projects forward over the top of the roll-breast, and these castings are pivoted at their inner ends to the connecting-rods C, and to each of the connecting-rods C is secured a supporting-roller, D, and these rolls support the breast in position. The top E of the roll-breast is here shown curved, so that as the roll-breast is forced backward by the pressure of the cotton in the roll-box the breast will rise upward, so as to enlarge or increase the size of the roll-box in two directions at the same time. This breast has arms F secured to its outer side so as to project beyond the ends of the roll-box, and through these arms are passed the set-screws G, which bear against the edges of the gin-head, and thus regulate the distance which the roll-breast shall move inward. By turning these screws inward the roll-breast can be moved outward from the gin-head, and thus increase the size of the roll-box; or by reversing the movement of the screws the gin-head will swing inward, so as to decrease the size of the roll-box. Also secured to the lower end of the roll-breast, in addition to the arms F, is a second set of arms, H, through which are also passed set-screws, and which arms and set-screws serve to throw the bottom of the roll outward, so as to regulate the escape of the seed from the roll-box. Where the seed do not escape freely enough from the roll-box the lower end of the breast can be moved outward; but should the seed be escaping too freely before the lint is thor-

oughly ginned from them, the breast can be moved inward, so as to prevent them from escaping before they have been thoroughly cleaned.

- 5 One great objection to the cotton-gin now in use has always been that the seed do not escape freely enough from the roll-boxes, and hence the roll will frequently be carrying around a large quantity of seed which should escape 10 from the box as soon as they are ginned. In order to prevent these seed from being thus carried around by the roll, I form in the outer side of the breast a series of slots, I, having any desired width between them, and then in- 15 side of this slotted plate I use a second sliding slotted plate, J, which can be adjusted endwise by means of suitable set-screws or other equivalent devices, so that the size of the spaces can be increased or diminished at will. With these 20 slots through the outer side of the roll-box the seed are forced out of the roll-box much more rapidly than they would escape through the usual space which is made through the bottom of the roll-box. It must be understood that 25 the seed are not wholly discharged from these slots, but that the slots are auxiliary to the usual discharge-opening through the bottom of the roll-box.

When the gin is to be fed by means of a gin- 30 feeder the roll K is pivoted in the end castings of the roll-breast, and the roll in the roll-box, bearing against this roll as it revolves, causes the roll to move with it, and this roll serves to catch the cotton which is being fed by the feeder and takes it directly into the roll-box. If, however, it should be desired to feed the machine by hand instead of by a feeder, this roller 35 may be removed, and then the hinged top L of the roll-breast may be turned forward and secured in the same position that was occupied 40 by the roller, and then a solid top is formed to the roll-breast. This solid top will be used when the gin is being fed by hand, instead of by a feeder; but this solid top will also be used 45 in connection with a feeder, if so desired.

The roll-boxes of some gins do not receive the cotton from the feeder as freely as they should, and hence the cotton is liable to pile up upon the top of the roll-breast and choke 50 the feeder, and where this is the case the roller is necessary to feed the cotton directly into the roll-box. Where the gin-box receives the cotton freely, or where the gin is to be fed by hand, the roll is not necessary.

55 The connecting-rods C are pivoted at their outer ends to the pivoted levers M, which are connected by the straps N to the lever O. When the roll-breast is forced backward by the pressure of the cotton in the roll-box, either 60 at one end or along its whole length, this backward movement is communicated through the connecting-rods C and the levers N to the lever O.

To the outer end of the lever O there are fastened 65 two wires, cords, or ropes, P Q, the one P being fastened nearest to the center of the

lever O, and either connected directly to a slide, R, or geared thereto through a roller, S. Where the roller S is used the gearing is increased, so as to make a very slight movement of 70 the lever O move the slide a greater distance.

The slide R is suspended in position by means of the spring T, and pivoted to this slide, and extending horizontally outward, is the pawl or dog U, which engages with the ratchet V on 75 one end of the roller of the apron which feeds the cotton to the large toothed drum. This slide is placed in a frame-work, W, which is pivoted at its lower end, and which has connected to its upper end the rod which connects 80 the frame with the crank on the end of the large toothed roller of the feeder. This toothed roller is driven by a belt from the shaft of the gin, and this roller, in turn, reciprocates the frame back and forth. As this frame rocks 85 back and forth, the dog or pawl is made to turn the ratchet, and thus feed the apron forward that carries the cotton to the toothed roller. In proportion to the speed at which the frame is reciprocated back and forth the apron will 90 be fed faster or slower, so as to deliver the cotton more rapidly or more slowly to the toothed roller.

Passing through the slide R is a suitable shaft, Y, which is provided with a thumb-nut, 95 Z, which can be turned so as to tighten or loosen the rope P. By drawing this slide downward by turning this shaft it will readily be seen that the pawl has a shorter movement, and hence will turn the ratchet of the feed-apron more slowly forward, and when the slide is allowed to rise upward by the pressure of the spring attached to its top the movement of the frame will give it a longer stroke, and thus the feed-apron will be moved more rapidly. 105

The rope, wire, or chain Q passes under the separate roller 1 of its own, and is fastened to the lower end of an ordinary spring-scale, 2. To the upper end of the spring-scale is secured a suitable cord, rope, or chain, 3, which can be 110 tightened or loosened by means of the small shaft 3', passing forward through the top of the frame, and having a thumb-nut attached to its outer end. This scale indicates the pressure at which the cotton is to be fed into the roll-box, and which pressure is supposed to be the 115 full capacity of the gin.

Extending upward from the top of the frame is the upright 4, to which is secured the horizontal arm, and passing up through this horizontal arm is a set-screw, 5. This set-screw is to be regulated up and down, and against the top of which the under side of the pawl strikes whenever the pressure in the roll-box has reached the limit at which it was set. 120

Screwed into the lower part of the upright is a second set-screw, 6, against which the end of the lever O is to strike when the pressure in the roll-box has exceeded its utmost capacity. The cotton should never be fed into the roll-box to such an extent that this lever will strike against the set-screw, for when the lever 125

is in contact with the set-screw then the breast is moved backward to that degree where the governor can no longer act.

The operation of my machine is as follows: 5 To set the governor so that it will regulate the size of the roll in the roll-box to the full capacity of the gin, the size of the roll must be first determined by experiment. When it has been discovered what size of roll the gin will 10 carry best, the pressure of the roll upon the breast is readily ascertained by putting the roll in the roll-box and allowing the roll to exert its power against the breast. This pressure of the roll against the breast is indicated 15 by the scale in pounds. The slide R is then drawn downward by means of the shaft Y and thumb-nut Z until the under side of the dog or pawl U strikes the top of the regulating set-screw 5. Until this dog does come in contact 20 with the set-screw 5 the rocking frame continues to feed the feed-apron forward; but should the cotton be fed into the roll-box so that the pressure exceeds even one pound beyond the limit which has been decided upon, 25 then the cord P, through the lever O, draws the slide farther down than the point at which it was set, and the under edge of the pawl striking against the set-screw 5, the outer end of the pawl is thrown out of gear with the ratchet 30 and the feed is immediately stopped. As soon as the pressure has been reduced so that it no longer exceeds the given limit the breast-roll moves inward toward the gin, and thus establishes the pressure upon the lever O, and this 35 lever then allows the slide R to move upward again to the position to which it was adjusted, and when it reaches this position the dog engages with the ratchet, and the oscillating movement of the frame causes the apron to be- 40 gin feeding the cotton again to the toothed roll. Should the pressure of the roll decrease considerably below the limit at which it was set, the roll-breast will move inward toward the gin sufficiently far to ease the pressure 45 upon the lever O until the slide can move upward to a higher point than the point at which it was adjusted, and as the stroke of the pawl is lengthened in proportion as the slide moves upward, it will readily be seen that at each 50 stroke of the frame the ratchet will be moved a greater distance, and thus the apron will be made to feed the cotton more rapidly to the roller and the roller will feed it more rapidly into the roll-box.

55 By the arrangement and combination of parts above described it is only necessary to adjust the pressure of the governor to any desired size of roll that is best suited to the capacity of the gin, and then the machine needs 60 no further attention. Should too much cotton at any time be fed into the roll-box, the governor will at once throw the feed out of gear until this overpressure has been reduced, and 65 should the feed at any time become too light, the rapidity of the speed is correspondingly

increased until the full pressure is reached. An operator to watch the gin to see that it does not choke is done away with, and the machine is made entirely automatic in its operation in every respect.

70 By the application of a governor, as above described, to a cotton-gin, the gin is kept ginning to its utmost capacity all the time, and hence it gins cotton with an evenness and regularity which can be acquired in no other way. 75 Where a gin is fed by hand the pressure frequently becomes so great as to choke the machine, and then time is lost in easing the pressure upon the saws, or the gin is not fed fast enough to run at its full capacity, and in either 80 case much time is lost. Where a governor is thus used a larger roll can be kept constantly in the roll-box and the gin made to do a much larger quantity of work in a given time than is now accomplished.

85 The principle of my invention consists in making the pressure of the cotton in the roll-box govern and control the whole mechanism by which the feeding is regulated. Instead of the breast being made movable, a movable roller 90 or other equivalent device may be used by making the roller movable back and forth while the breast remains stationary.

Having thus described my invention, I claim—

- 95 1. In a cotton-gin, the combination of a movable or oscillating roll-breast or roller with a suitable mechanism connected thereto and operated by the pressure of the roll in the roll-box, substantially as shown.
- 100 2. In a cotton-gin, the combination of a movable or oscillating roll-breast, suitable connecting-rods, a scale for indicating the pressure, and a mechanism for throwing the feeder out of gear when the limit of pressure is reached, 105 substantially as described.
- 110 3. In a cotton-gin, a roll-breast having slots made through its outer side for the escape of the seed, substantially as set forth.
- 115 4. The combination of a roll-breast, having slots through its outer side for the escape of the seed, with a regulating-slide for controlling the size of the slots, substantially as specified.
- 120 5. In a cotton-gin, a movable roll-breast provided with suitable supporting-rollers, whereby it is movably supported in position upon the gin, substantially as shown.
- 125 6. In a cotton-gin, a roll-breast provided with arms F and set-screws G, whereby the roll may be prevented from moving inward for the purpose of increasing the size of the roll-box, substantially as described.
- 130 7. In a cotton-gin, the combination of a roll-breast, connecting-rods C, a series of levers connected to the lever O, the cords P Q, the slide provided with a pawl for operating the feed-apron, and a spring for denoting the pressure, substantially as set forth.
8. The combination of a reciprocating frame, a slide, R, the set-screw 5, the dog U, and the

ratchet of the feed-apron, substantially as specified.

9. In a governor for cotton-gins, the combination of the two feed-rolls, a connecting-rod, a crank for reciprocating the frame, an adjustable slide, the dog R, and set-screw 5, substantially as shown.

10. In a cotton-gin, a roll-breast that is disconnected from the frame of the gin, and which

can adjust itself to the size of the roll in the box, substantially as described.

In testimony whereof I affix my signature in presence of two witnesses.

L. D. FORBES.
